DISPENSING RACK

Charles Strauss, Chicago, Ill., assignor to Arvey Corporation, Chicago, Ill., a corporation of Illinois

Application May 6, 1944, Serial No. 534,407

5 Claims. (Cl. 242—55.5)

This invention relates to dispensing racks for rolled sheet material such as paper, fabric and the like.

It is an object of the present invention to provide a dispensing rack and holder for rolled sheet material of a simple but rugged construction adapted to firmly and securely support relatively heavy as well as lighter rolls of material for dispensing purposes, the rack being constructed in a manner whereby the rolls of material to be supported and dispensed may be quickly, conveniently and securely positioned and engaged, and securely positioned and supported for dispensing purposes without undo binding action, the rack being further adapted to be readily secured to a fixed mounting surface such as counter, wall or shelf.

In general my invention comprises a unitary rack which includes a pair of spaced roll supporting brackets and base support means therefor, one of the brackets being in fixed engagement with its base support and the other being pivotally engaged adjacent one of its lateral edges to its base support for lateral movement thereon about an axis perpendicular to its base support, and means extending between the pivotally engaged bracket and its supporting base for either permitting the movable bracket to be swung laterally for the purpose of engaging or disengaging a roll of sheet material or for securing the bracket against pivotal movement in a position parallel to the fixed bracket for supporting the roll of sheet material in dispensing position.

Other objects relate to the details of construction, arrangement of parts and the advantages and economies thereof which will be apparent from a consideration of the following specification and drawing wherein:

Fig. 1 is a plan view with parts broken away of my novel dispensing rack.

Fig. 2 is a side elevation thereof.

Fig. 3 is a section on the line 3—3 of Fig. 2.

Fig. 4 is an end elevation viewed on the line 4—4 of Fig. 2.

Fig. 5 is a section on the line 5—5 of Fig. 3, but with the bracket in outwardly pivoted position.

Referring to the drawing the dispensing rack comprises a pair of roll supporting brackets 10 and 11 adapted to be positioned in spaced parallel relationship to each other for supporting a roll of sheet material, indicated as 12, by suitable means such as the discs or rollers 13 rotatably engaged against the inner faces of the brackets by means of screws 14. The brackets 10 and 11 are provided with base support members 15 and 16 respectively, for permitting the

rack to be engaged as a unit to a fixed supporting surface 17, which may be wall, table, shelf or the like, the brackets 15 and 16 being secured to the mounting surface 17 by suitable screws generally indicated as 18 extending through the base support pieces 15 and 16.

The bracket 11 is fixedly secured to its supporting base 16 by means not shown, which may be, for example screws or glue. The bracket 10 is 10 pivotally secured to its base support member 15 adjacent one of its lateral edges by means of the pivot 19 extending from the base piece 15 into the base of bracket 10, so as to permit the bracket 10 to be pivoted laterally and to thereby permit 15 engagement onto or removal of a roll of sheet material 12 from the rollers 13.

The bracket 10 is further adapted to be maintained in fixed parallel relationship to the fixed bracket 11 in normal or dispensing use by being 20 formed with a face groove 20 extending transversely of and across the laterally projecting leg 21, the groove being adapted to receive the bolt 22 extending from the base piece 15, and when the bolt 22 is seated within the groove 20, the bracket 25 10 may be locked in fixed position by means of the wing nut 23 carried by the bolt 22.

Extending transversely of and between the brackets 10 and 11 is the cut-off bar 24 which 30 may be relatively wide and in addition to its function as a cut-off bar, serves as a tie member for the brackets 10 and 11, and may also provide a suitable advertising display surface. When the rack is utilized for sale and display of the supported roll material, the cut-off bar 24 is held 35 suspended in a laterally projecting position, parallel to the roll 12, by means of the angle supporting pieces 25 and 26, the bar 24 being secured to one pair of legs of the angular pieces 25 and 26. Both of the bars 25 and 26 may be secured to the 40 heads of their respective brackets 10 and 11 by suitable screws, and the angle piece 26 may be suitably secured to its bracket 11 by means of the two screws 27. However, the angle piece 25 is secured to the head of its bracket 10 by means of 45 a single screw 28, the screw 28 extending parallel to the pivot 19 which extends from the base piece 15 into the bottom of the bracket 10, that is, the bracket 10 is pivotally engaged between both the base support member 15 and the angle piece 25.

50 It will thus be evident that my dispensing rack may be quickly and conveniently mounted on a suitable supporting surface and adapted for use with rolls of sheet material of suitable length controlled by the length of the cut-off board 24, 55 which may be provided in desirable or suitable

lengths. It will likewise be apparent that the rack although of simple construction is rugged and adapted to hold rolls of sheet material of either light or relatively heavy weight which may be quickly and conveniently engaged and disengaged without the requirement or interpositioning of spring means, but rather by the provision of a simple pivotal engagement and locking means, illustrated and previously described, one of the roll supporting brackets may be quickly and conveniently moved into and out of supporting relationship with the roll material, and quickly and conveniently locked or unlocked in such position.

I claim as my invention:

1. A dispensing rack and holder for rolled sheet material comprising a pair of spaced roll supporting brackets, base support means therefor and a tie member extending between and disposed adjacent the heads of the brackets, one of said brackets being in fixed engagement with its base support and said tie member and the other being pivotally engaged adjacent one of its lateral edges to said tie member and to its base support for lateral movement thereon about an axis perpendicular to said base support.

2. A dispensing rack and holder for rolled sheet material comprising a pair of spaced roll supporting brackets, base support means therefor and a rigid tie member extending between the brackets and supported from arms secured to the bracket heads, one of said brackets being in fixed engagement with its base support and a tie member support arm and the other being pivotally engaged adjacent one of its lateral edges to the other tie member support arm and to its base support for lateral movement thereon about an axis perpendicular to said base support, and means extending between said pivotally engaged bracket and its supporting base for securing the bracket against pivotal movement in a position parallel to said fixed bracket.

3. A dispensing rack and holder for rolled sheet material comprising a pair of spaced roll support-

ing brackets, base support means for said brackets and cut-off bar means secured to and extending between said brackets, one of said brackets being in fixed engagement with its base support and the other being pivotally engaged adjacent one of its lateral edges to and between its supporting base and said cut-off bar means.

4. A dispensing rack and holder for rolled sheet material comprising a pair of spaced parallel roll supporting brackets, a cut-off bar extending between and projecting laterally of said brackets, suspension support means for said cut-off bar secured to the heads of said brackets, and base supports for said brackets for mounting said rack

15 on a fixed supporting surface, one of said brackets being in fixed engagement with its base support and the other being pivotally engaged adjacent one of its lateral edges to and between its base support and the cut-off bar suspension support

20 means for lateral movement on an axis perpendicular to said base support, and means for maintaining said moveable bracket in fixed supporting position parallel to the fixed bracket.

5. A dispensing rack and holder for rolled sheet material comprising a pair of spaced parallel roll supporting brackets, a cut-off bar extending between and projecting laterally of said brackets, suspension support means for said cut-off bar secured to the heads of said brackets, and base supports for said brackets for mounting said rack on a fixed supporting surface, one of said brackets being in fixed engagement with its base support and the other being pivotally engaged adjacent one of its lateral edges to and between its base support and the cut-off bar suspension support

30 means for lateral movement on an axis perpendicular to said base support, and means formed on said moveable bracket adjacent the base thereof engageable with means projecting from its base support for locking it in fixed position parallel to the fixed bracket.

CHARLES STRAUSS.
